UNITED STATES PATENT OFFICE

91,871

DESIGN FOR A CURTAIN

Hugo Geller, New York, N. Y., assignor to Patchogue-Plymouth Mills Corporation, New York, N. Y., a corporation of New York

Application December 6, 1933, Serial No. 49,969

Term of patent 14 years

To all whom it may concern:

Be it known that I, Hugo GELLER, a citizen of the United States, residing in the Borough of Manhattan, county of New York, and State of New York, have invented a new, original, and ornamental Design for a Curtain, of which the following is a specification, reference being had to the accompanying drawing, forming part thereof.

The figure is a plan view of a curtain showing my design.

What is claimed is:

The ornamental design for a curtain as shown.

HUGO GELLER.
